(57) **CLAIM**

The ornamental design for a digital audio disc player for vehicle, as shown and described.

DESCRIPTION

FIG. 1 is a front, top and left-side perspective view of a digital audio disc player for vehicle showing my new design; FIG. 2 is a front elevational view thereof; FIG. 3 is a rear elevational view thereof; FIG. 4 is a top plan view thereof; FIG. 5 is a bottom plan view thereof; FIG. 6 is a right-side elevational view thereof; and, FIG. 7 is a left-side elevational view thereof.

The broken lines of the drawings represent portions of the digital audio disc player for vehicle that are not part of the claimed design.
